UNITED STATES PATENT OFFICE.

MARSHALL KNIGHT THAYER, OF EDGEWOOD, SOUTH DAKOTA.

VAPORIZER.

1,345,563.

Specification of Letters Patent.

Patented July 6, 1920.

Application filed October 20, 1919. Serial No. 331,980.

To all whom it may concern:

Be it known that I, MARSHALL KNIGHT THAYER, a citizen of the United States, and a resident of Edgemont, in the county of Fall River and State of South Dakota, have invented certain new and useful Improvements in Vaporizers, of which the following is a specification.

My present invention relates generally to internal combustion motors and more particularly to heating means therefor, whose function is to warm up and limber the motor when cold and the object of my invention is to provide a simple comparatively inexpensive apparatus of this nature, which will not interfere in any way with the normal operation of the motor when once warmed up and which will be readily accessible, and easily perform its intended functions previous to starting.

It is a well known fact that internal combustion motors, particularly automobile motors are difficult to start after standing and becoming chilled, and that the major reason for this difficulty arises from the congealed lubricating oil in the cylinders, resulting in stiffening the action of the motor and so impairing compression as to prevent effective action in drawing in the proper charges of gas.

The difficulty referred to also results from insufficient vaporization of the gas mixture and it is the further object of my invention to provide means whereby external combustion may be developed and the products thereof sucked directly into the working cylinders through the intake pipe so as to alleviate the conditions bringing about difficult starting both as to the lubricating oil and the gas mixtures.

I therefore propose to slot the intake pipe of a motor and provide means forming a fuel chamber so located with respect to the slot as that the products of combustion of fuel oil in the chamber may be drawn into the intake pipe and from thence into the working cylinder so as to liquefy the congealed lubricating oil and at the same time heat the intake pipe through which the combustible gas mixture will subsequently pass to the working cylinders.

My invention also proposes that the means forming the fuel oil chamber shall at the same time be so located with respect to the slot of the intake pipe as to avoid the danger of influx of the fuel oil itself

into the intake pipe, and contemplates the provision of a cover or closure for the fuel oil chamber by means of which ingress of air into the intake pipe slot may be prevented during normal operation of the motor.

With the above in mind, my invention will be better understood from the following description of several forms thereof, shown in the accompanying drawings, to which the description refers. In these drawings which form a part of this specification,

Figure 1 is a front elevation illustrating my invention integrally formed and applied in connection with a motor intake pipe,

Fig. 2 is a side view thereof,

Fig. 3 is a sectional plan view,

Fig. 4 is a vertical transverse section,

Figs. 5 and 6 are respectively a front elevation and a vertical transverse section through my invention applied as a separate part to an intake pipe already in use, and

Fig. 7 is a sectional side view illustrating another slightly modified form of the invention applied to a portion of a motor intake pipe and illustrating its intended functions.

Referring now to these drawings and particularly to Figs. 1 to 4 inclusive, my invention proposes the provision of a motor intake pipe generally indicated at 10 with a transverse slot 11 through its wall and extending partially therearound, this slot being inclined with respect to a right angle and being continued in inclined relation through an enlargement 12 which extends partially around the pipe 10 for at least the length of the slot 11.

Below the slot 11, pipe 10 has an outstanding horizontal flange 13 which constitutes the base of a fuel oil chamber 14 having along its outer edge an upstanding flange 15, forming the chamber wall.

It will thus be noted that the fuel oil chamber 14 is of arcuate shape, extending as it does partially around the pipe 10, and entirely below the level of the upper outer end of the inclined slot 11, which latter is thus adapted to take in the products of combustion from the chamber 14, without danger of influx of the fuel oil into the intake pipe 10.

Above the plane of the chamber 14 is a cover 16 provided with side extending ears 17, the latter of which are hingedly connect-

ed by pivot bolts 18 to diametrically opposite points of the pipe 10. This cover has an outer depending flange 19 which externally laps the upper edge of the flange or 5 wall 15 of the fuel oil chamber and has an inner arcuate flange 20 which abuts a co-operating flange 21 of the pipe enlargement 12 so that the cover may be readily closed in air-tight relation on the fuel oil chamber 10 and held by a set screw 22 which works therethrough and screws into a threaded vertical bore of the chamber wall 15.

In this way, the normal operation of the 15 motor can proceed without danger of being adversely effected by intake of air through the slot 11.

In the form of the invention shown in Figs. 5 and 6, a fuel oil chamber 14^a is formed of arcuate shape by means of a base 20 13^a and an upright outer wall 15^a, the slot 11^a of the pipe 10^a being extended in this instance through the upper enlargement 12^a of an inner wall 23 of the chamber.

This inner wall which is curved to fit the 25 contour of the pipe 10^a, has at its opposite ends upper and lower apertured ears 24 to receive clamping bolts or screws 25 extending also through the ears 26 at the opposite ends of the pipe embracing straps 27 shown 30 particularly in Fig. 6, so as to thus hold the fuel oil chamber forming means in proper position in connection with the pipe 10^a and in the desired location relative to the pipe slot 11^a. In this form the cover 16^a which 35 is formed like the cover 16 of the construction of Figs. 1 to 4 inclusive is hinged at 18^a to the upper side portions of the inner wall 23 instead of directly to the pipe as in the former case.

40 In Fig. 7 I have shown my invention as applied in the length of the intake pipe between sections 10^b and 10^c and in the nature of a plate 28 disposed and clamped between the adjacent ends of these sections, plate 28 45 having a bore alining with the pipe bores and thus forming in effect a part of the intake pipe. Plate 28 has a slot 29 which in this instance projects vertically through an upper extension 30 of the plate and terminates within the extreme upper portion of a lateral enlargement 31 of extension 30 which enlargement forms a liquid fuel chamber 32. In this construction a cover 33 is hingedly connected directly to the 50 upper end of extension 30 so as to cover the entire upper end of chamber 32, and has a connecting screw 34 for engagement in an opening 35 in the outer wall of the chamber. The liquid fuel chamber in this instance, like the liquid fuel chambers formed 55 according to the previously described constructions, may have an inner absorbent member 36 stationarily held by a screw 37, which will hold a quantity of liquid fuel.

60 It is obvious that all of the forms of con-

struction serve the same function as regards the delivery of products of combustion upon ignition of a quantity of hydrocarbon fuel within the liquid fuel chambers through the slot of the intake pipe and into the intake 70 pipe for passage under the suction of the motor through its intake valves and into its working cylinders as indicated by the arrows in Fig. 7. For this purpose the crank shaft of the motor is turned over by hand 75 with the throttle valve closed and the entrance of the products of the combustion will serve to quickly and effectively liquefy the congealed lubricating oil so as to enable the motor to promptly reach its normal efficiency as regards compression in the working cylinders. Thus by turning over the crank shaft but a very few times, the motor will have reached the stage where it can effectively suck in its own charge, and the 80 cover of the liquid fuel chamber can then be closed which will serve to damp out the flames and the throttle valve may then be opened after the cover is secured in air-tight relation by the means previously described.

It is also to be noted that during the feeding of products of combustion of the fuel chamber to the working cylinders, the intake pipe will itself be heated so as to bring about 95 efficient vaporization of the gas and in this way all of the parts will be advantageously affected in the interest of quick, efficient starting no matter how cold the motor may have previously been.

I claim:—

1. The combination with the intake pipe of a combustion motor having a slot in its wall, means forming a liquid fuel chamber adjacent to and on a level below the outer 105 end of said slot whereby products of combustion within the chamber may be drawn in the pipe slot without danger of influx of the fuel oil, and a cover normally closing the fuel chamber and the said slot.

2. The combination with the intake pipe of a combustion motor having a slot transversely through its wall and extending partially therearound, of means forming a liquid fuel chamber adjacent to the pipe and extending therearound for the full length of the slot, said slot being in communication at its outer end with the upper portion of the said liquid fuel chamber, and a closure for the liquid fuel chamber arranged to also cut 115 off external communication of the said slot.

3. The combination with the intake pipe of a combustion motor having a transverse slot extending partially therearound, means forming a liquid fuel chamber with the upper portion of which the outer end of the slot communicates at a point spaced from the pipe, said chamber forming means extending around the pipe for the full length of the slot and a closure for the chamber ar- 125 130

ranged to cover the outer end of the slot, as described.

4. The combination with an intake pipe of a combustion motor having a transverse slot extending partially therearound, means forming a liquid fuel chamber with the upper portion of which the outer end of the slot communicates at a point spaced from the pipe, said chamber forming means extending around the pipe for the full length of the slot and a closure for the chamber arranged to cover the outer end of the slot, said closure being hinged adjacent to opposite sides of the pipe to swing toward and away from the fuel holding chamber, as described.

5. The combination with the intake pipe of a combustion motor, having a transverse slot extending partially therearound, means forming a liquid fuel chamber and including an inner wall partially embracing the pipe and provided with an enlargement slotted to register with the pipe slot, and the inner end of the slot of which communicates with the upper portion of the said chamber at a point spaced from the pipe, and a closure for the chamber having flanged portions to overlap the upper edges of its walls, as described.

6. The combination with the intake pipe of a combustion motor having a transverse slot extending partially therearound, means forming a liquid fuel chamber adjacent to the slot, including an inner wall slotted to register with the slot of the pipe and partially embracing the pipe, connecting straps

embracing the remaining portion of the pipe and connected to the said inner wall to securely hold the latter in position, said chamber having an outer wall, and a cover arranged to snugly engage the upper edges of the said inner and outer walls.

7. The combination with the intake pipe of a combustion motor having a transverse slot extending partially therearound, means forming a liquid fuel chamber adjacent to the slot, including an inner wall slotted to register with the slot of the pipe and partially embracing the pipe, connecting straps embracing the remaining portion of the pipe and connected to the said inner wall to securely hold the latter in position, said chamber having an outer wall, and a cover arranged to snugly engage the upper edges of the said inner and outer walls, said cover having extensions hinged adjacent to the opposite sides of the intake pipe to swing toward and away from the liquid fuel chamber, as described.

8. The combination with the intake pipe of a combustion motor having a slot in its wall, means forming a liquid fuel chamber adjacent to and on a level below the outer end of said slot whereby products of combustion within the chamber may be drawn in the pipe slot without danger of influx of the fuel oil, a cover normally closing the fuel chamber and the said slot, and means for securing the cover in air-tight relation over the chamber.

MARSHALL KNIGHT THAYER.
